(57) CLAIM

The ornamental design for a case for an electronic device as shown and described.

DESCRIPTION

FIG. 1 is a front, first side, and top perspective view of a case for an electronic device embodying the new design; FIG. 2 is a front, second side, and top perspective view thereof;

FIG. 3 is a front, second side, and bottom perspective view thereof;

FIG. 4 is a front, first side, and bottom perspective view thereof;

FIG. 5 is a back, second side, and top perspective view thereof;

FIG. 6 is a front view thereof;

FIG. 7 is a back view thereof;

FIG. 8 is a first side view thereof;

FIG. 9 is a second side view thereof;

FIG. 10 is a top view thereof; and,

FIG. 11 is a bottom view thereof.

The broken lines indicate portions of the case for an electronic device that form no part of the claimed design.

1 Claim, 11 Drawing Sheets
